CLAIM

The ornamental design for a high frequency therapy device, as shown and described.

DESCRIPTION

FIG. 1 is a perspective view of a high frequency therapy device showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line shown in the drawings is included for the purpose of illustrating portions and environmental elements of the high frequency therapy device and forms no part of the claimed design.
